PUMP

Charles H. Moneypenny, Detroit, Mich.

Application May 5, 1932, Serial No. 609,482

3 Claims. (Cl. 103—89)

My invention relates to pumps and particularly to machine tool pumps designed to handle coolants or lubricants, but is not necessarily limited to this class of pumps.

5 It is an object of the present invention to provide a pump assembly which is composed of relatively few simple parts and which may be readily disassembled for repair, replacements or adjustment.

10 It is also an object of the invention to provide a pump which will not lose its prime when not running and which will not eject its prime if run in reverse.

Another object of the invention is to provide 15 a cap plate carrying the discharge outlet and which may be quickly and easily adjusted to dispose the discharge outlet in any position desired.

Another object of the invention is to provide an improved form of impeller member.

20 A further object of the invention is to provide an improved form of mounting for the impeller.

A still further object of the invention is to 25 provide improved lubricating means for the bearings of the impeller.

Other important objects and advantages of the invention and not specifically referred to will 30 become apparent during the course of the following detailed description, when read in conjunction with the accompanying drawings, which form a part of this specification and in which:

Fig. 1 is a central vertical section through the assembled pump.

Fig. 2 is an end elevation of the discharge end 35 of the cap plate in one position of adjustment.

Fig. 3 is a similar view showing the cap plate in another possible position of adjustment.

Fig. 4 is an enlarged section of the shaft packing.

40 Fig. 5 is a side elevation of my improved impeller member.

Fig. 6 is an end elevation looking to the left on Fig. 5.

Fig. 7 is an end elevation looking to the right 45 on Fig. 5.

Fig. 8 is a flat template layout of the design of the blades on the surface of the impeller, and

Fig. 9 is a fragmentary view of an alternative method of sealing the outer end of the center 50 bore of the cap plate.

Referring now to the drawings in detail, and particularly to Figs. 1 to 4, 10 indicates the housing of the pump, which is formed with a suitable base 11 and a substantially conical impeller chamber 12 within which is mounted an impeller member 13 in the form of a conical body having spiral blades 14 formed on the slanting face thereof, the particular structure and design of which will later be described in detail. It will be noted 60 that the taper of the walls of the chamber 12

is substantially the same as that of the impeller body, so that the distance therebetween is equal at all points.

The housing 10 at the larger end of the impeller chamber 12, terminates into a circumferential rim 15 which has the end face thereof machined off to provide a seat for a cap plate 16 which closes the open end of the chamber 12, and which is formed with an open volute channel 17 on the inner face thereof which is of 10 gradually increasing depth and which terminates into a discharge outlet fitting 18 for the connection of a suitable discharge pipe (not shown).

The cap plate 16 is formed with an annular flange 19 which overlies the periphery of the 15 rim 15 and which carries a plurality of circumferentially spaced and pointed set screws 20 which engage the slanting wall of a groove 21 formed in the peripheral edge of the rim 15 to draw the cap plate into sealing engagement with 20 the end of the housing 10 and to lock the same in position. It will readily be seen that this novel method of securing the cap plate to the housing permits rotary adjustment of the cap plate so as to permit placing of the discharge outlet in 25 any desired circumferential position, as illustrated in Figs. 2 and 3, and also does away with forming bolt holes in the gasket 22 which is interposed between the cap plate and the end of the housing 10.

The small end of the impeller chamber 12 opens 30 into an inlet or prime chamber 23 which is provided with an inlet opening 24 at the top thereof to which a pipe leading to the source of liquid supply may be readily attached. By having 35 the inlet lead into the top of the inlet chamber 23, the prime in the pump is not drained when the pump is not operating and the piping can be conveniently carried down to the source of supply from either side.

The pump housing 10 and cap plate 16 are 40 formed with axially aligned hollow bosses 25 and 26 respectively within which the respective ends of the shaft 27 of the impeller 13 are journaled in ball bearings 28 and 29, the bearing 28 having 45 the outer race 30 thereof resting against an inwardly directed shoulder 31 formed within the bore of the boss 25, while the outer race 32 of the bearing 29 has a sliding fit within the bore of the boss 26.

The shaft 27 is provided with oppositely directed rounded shoulders 33 and 34 against which the inner races 35 and 36 of the bearings 28 and 29 are seated, and a compression spring 37 confined between the bearing race 32 and a threaded sealing plug 38 which closes the outer end of the bore of the boss 29 provides an end thrust on the shaft 27 and serves to keep the bearings tight and in place. This spring also provides a yielding means to permit the entire impeller assembly 60

to give slightly in an axial direction in case some hard foreign matter should become wedged between the impeller blades and the surface of the impeller housing.

5 Suitable grease or oil seals 39 are disposed within the bores of the bosses 25 and 26 between the bearings 28 and 29 and the pumping chamber so as to seal the space around the shaft and protect the bearings from contact by the liquid being pumped. These seals, as shown in Fig. 4, include a flared circular ring or blade 40 which is spring-pressed against a felt or leather packing member 41 to maintain the latter in close contact with the shaft 27, the entire body of the seals being pressed into position within the bores of the bosses and maintained therein by frictional contact. Set screws may be employed to further secure the seals in their proper positions, if desired. A similar seal 42 closes the outer end 20 of the bore of the boss 25 around the protruding end of the shaft 27 to which any suitable driving means for the impeller may be connected.

25 Pressure grease fittings 43 are carried by the bosses 25 and 26 for feeding lubricant into the chambers behind each of the bearings 28 and 29. By mounting the grease seals with the edge of the blades 40 facing the pump chamber, old grease may be forced out through the seals into the pumping chamber and thus carried away 30 with the liquid being pumped.

35 Referring now more particularly to Figs. 5 to 8, the body of the impeller 13 is substantially cone-shaped and the blades 14 are generated on the surface thereof in substantially spiral form. The impeller body may be secured on the shaft 27 by means of a press fit or may be keyed thereon.

40 The blades 14, which may be in any desired number or depth found most desirable, are spaced equal distances apart adjacent the small end of the impeller body and continue in a spiral path to the base end, where they are flattened out as at 43 to lie in a plane substantially at right angles to the shaft 27 and overlying the volute channel 45 17 in the cap plate 16.

45 The back face of the impeller body is concave or dished, as clearly shown in Figs. 1 and 6, and is provided with blades 44 which extend in a slight curve from the central area of the base and merge with the free ends of the flat portions 43 of the blades 14. These blades 44 serve to discharge any foreign matter or liquid that would otherwise collect behind the impeller body.

50 In Fig. 8 is shown a flat template illustrating the design and layout of the blades 14 on the surface of the conical body 13, with the exception of the flattened portions 43 thereof. In the design shown, B is the slant height of the frustum of the cone surface of the impeller body. A is one half of the total circumference of the cone, and E is a point where a radial line bisecting the dimension A crosses a circumferential line bisecting the dimension B. The points C and F are points at the base and apex of the cone template at opposite extremities of the dimension A.

55 Thus a line representing the center of a blade and starting at F and describing an arc passing through the point E and terminating at the point C will have traveled one-half of the total circumference and will be a true arc of a circle with the radius R. The length of the radius R and

the location of the radius point D will vary with the size and angle of the sides of the impeller body.

Fig. 9 illustrates an alternative method of sealing the end of the hollow boss 26, wherein an expansion plug 45 is forced into position in the countersunk outer end of the bore, being held therein by frictional engagement effected by expanding the plug from the dotted- to the full-line position.

10 In operation, upon rotation of the impeller in a clockwise direction, liquid will be drawn by the blades up against the conical surface and accelerated in action as it draws near the rim at the large end of the body where it is forced into 15 the channel 17 and through the outlet by the flattened portions 43 of the blades 14.

15 It will be noted that there are no revolving parts within the pumping chamber dependent upon closely machined and fitted parts for efficient operation, thus the pump will be practically immune to trouble due to wear of the parts. Since the spring 37 provides means to prevent jamming and breakage due to foreign matter becoming caught between the blades and the housing, the pump is practically trouble and wear proof.

20 In the form illustrated, the pump is designed to run in a clockwise direction. By reversing the paths of the outlet channel and impeller blades, the pump could be run in a counterclockwise direction without further alterations.

25 While a preferred embodiment of the invention has been shown and described, it will be understood that various changes in the details of construction and operation may be resorted to without departing from the spirit of the invention within the scope of the appended claims.

I claim:

1. A pump impeller comprising a conical body 40 portion, substantially spiral blades formed with said body portion, each of said blades comprising an arcuate portion beginning adjacent the apex of said body and extending in an arcuate path around one-half the circumference of said body 45 portion to the base thereof, said arcuate portion of each of said blades passing through a point one-half of the circumferential distance between the terminals thereof and one-half the height of the conical body, said blades when laid in flat 50 pattern forming an arc one-half the circumference of a true circle.

2. A device according to claim 1 and, substantially radially disposed curved blades formed with the base end of said impeller body. 55

3. A pump impeller comprising a conical body portion, substantially spiral blades formed with said body portion, each of said blades comprising an arcuate portion beginning adjacent the apex of said body and extending in an arcuate path around substantially one-half the circumference of said body portion to the base thereof and terminating in a flattened portion of substantial area disposed at substantially right angles to the axis of the impeller body and forming a continuation of the base end thereof, and substantially radially disposed curved blades formed with the base end of said impeller body and merging at their outer ends with the back of the free ends 60 of said flattened portions. 65

70 CHARLES H. MONEYPPENNY.
